UNITED STATES PATENT OFFICE.

ZERO MARX, OF CHICAGO, ILLINOIS.

DESIGN FOR AN ASH-BOWL.

SPECIFICATION forming part of Design No. 16,573, dated March 16, 1896.

Application filed January 29, 1896. Serial No. 190,241. Term of patent 7 years.

To all whom it may concern:

Be it known that I, ZERO MARX, a citizen of the United States of America, residing at Chicago, in the county of Cook and State of Illinois, have invented a certain new and original Design for Ash-Bowls, of which the following is a specification, reference being had therein to the accompanying drawings, in which—

10 Figure 1 represents a perspective view, and Fig. 2 a vertical section thereof, these two views being deemed necessary to fully illustrate my design.

15 The leading features of my design consist in a hollow vessel representing a druggist's mortar and a cross-bar in conventional representation of a pestle, the latter extending across the open mouth of the bowl, and being bent upwardly at one end beyond the upper edge 20 of the vessel's mouth.

In the drawings, A is the ash-bowl, in design similar to a druggist's mortar; b, the cross-bar representing the pestle, and B the upwardly-bent end thereof.

What I claim is—

The design for an ash-bowl herein shown and described, the same consisting of a hollow vessel representing a druggist's mortar, and containing a cross-bar in conventional representation of a pestle, the same extending directly across the open mouth of the bowl, and having one of its ends bent upward at an obtuse angle and projecting beyond the periphery of the vessel's mouth.

30 In testimony whereof I affix my signature 35 in presence of two witnesses.

ZERO MARX.
